CLAIM

The ornamental design for a display screen with graphical user interface for controlling machine tools, as shown and described.

DESCRIPTION

FIG. 1 is a front view of the first image in a sequence for a display screen with graphical user interface for controlling machine tools showing our new design;

FIG. 2 is a left side elevational view thereof;

FIG. 3 is a top plan view thereof;

FIG. 4 is an enlarged view of the design shown in FIG. 1, showing the first image in a sequence;

FIG. 5 is an enlarged view of the design, showing the second image in a sequence; and,

FIG. 6 is an enlarged view of the design, showing the third image in a sequence.

The appearance of the transitional image sequentially transitions between the images shown in FIGS. 4-6. The process or period in which one image transitions to another image forms no part of the claimed design.

The broken line showing of the display screen is for the purpose of illustrating portions of the display screen and forms no part of the claimed design.

1 Claim, 6 Drawing Sheets
